United States Patent Office

Des. 200,276
Patented Feb. 9, 1965

200,276

AIRPLANE

Irven H. Culver, Sunland, John B. Pitkin, Arcadia, and
William H. Statler, Northridge, Calif., assignors to
Lockheed Aircraft Corporation, Burbank, Calif.

Filed June 11, 1964, Ser. No. 80,363

Term of patent 14 years

(Cl. D71—1)

FIG. 1

FIG. 2

FIG. 3

FIG. 4

FIGURE 1 is a perspective view of an airplane embodying our design;

FIGURE 2 is a bottom view thereof;

FIGURE 3 is a side view thereof; and

FIGURE 4 is a front view thereof.

The dominant features of our design reside in those portions shown in full lines.

We claim:

The ornamental design for an airplane, substantially as shown and described.
